UNITED STATES PATENT OFFICE.

JONAS NORTHRUP, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

DETECTOR MECHANISM FOR LOOMS.

Application filed December 5, 1924. Serial No. 754,064.

The present invention relates to an improvement in detector mechanisms for looms. The object of the invention is to reorganize and improve the construction of the mechanisms by which weft detectors operate to stop the looms or cause weft replenishment in looms, and to this end the invention consists of the mechanisms hereinafter described and particularly defined in the claims.

In the accompanying drawing illustrating the preferred form of the invention Fig. 1 is a plan of a detector slide, and Fig. 2 is an elevation partially in section.

The illustrated embodiment of the invention is described as follows: The weft detector or fork 10 is pivotally mounted at 11 on the detector slide 12 slidably supported on the detector slide bracket 13, which cooperates with a knock-off lever to knock off the loom and also with a weft replenishing mechanism to cause weft replenishment, as illustrated in the Jonas Northrop Patent No. 1,186,933. The slide is provided with a misthreading device indicated in a general way by the reference character 14 illustrated in said patent. A weft hammer 15 carries at its upper end a weft hammer hook 16 pivoted to the weft hammer on the pin 17 and normally held in depressed position by the spring 18 placed on one side of the pin 17, as shown in Fig. 2. The weft hammer hook 16 is provided with a barb 19 adapted to engage the tail 20 of the fork 10. When the lay beats forward, the weft, lying across the grid, strikes the tines of the fork 10 and tips the fork so as to lift the tail of the fork above the barb; then upon the forward movement of the weft hammer the barb passes under the tail of the fork, and the hammer moves forwardly without imparting movement to the detector slide. On the forward movement of the weft hammer the flat under surface 21 of the weft hammer hook slides upon the plate 22 of the detector slide 12 so that the hook has a movement forward and backward with respect to the detector slide, except in the absence of yarn in front of the grid, in which case the fork is not tilted, and the barb of the hook engages the tail of the fork and pulls upon it to move the detector slide forwardly. Upon the first forward movement

of the slide weft replenishment is called for in the usual manner. After a number of weft replenishing attempts, the loom is knocked off and comes to rest. The weft hammer hook is provided with an overhanging guard or finger 23 which extends upwardly from the body of the hook and thence rearwardly over the fork. When thread is present in front of the grid on the lay and the fork is thereby tipped lifting the tail 20 of the fork, it is held tipped until the weft hammer has moved forwardly sufficiently to move the barb of the hook beyond the cross member of the tail, whereupon the tail engages the tail-supporting surface 24 of the hook which extends from the barb to the knuckle 25 of the finger 23; then during the further forward movement of the hook the tail of the fork slides on this tail-supporting surface. The under side of the finger 23 is so shaped that it engages a portion of the fork and prevents it from overthrowing. Thus when the fork strikes the yarn it is tilted with more or less violence, and that tips the tail up until the body of the tail strikes the under side of the finger. This prevents overthrow of the fork, and the fork is thereafter prevented from dropping back to its original position by reason of the tail-supporting surface of the finger which engages the tail. When the weft hammer moves rearwardly, the tail slides down the inclined surface of the hook and drops over the barb at the extreme end of the rearward movement of the weft hammer. The tail falls but a short distance, and rebound of the tail does not occur.

The detector fork 10 comprises a body portion consisting of the main part 26 having a hole through which the pivot 11 passes, and the cover 27 which consists of a flat piece of metal having a hook 28 at its forward end which engages the forward end of the part 26 of the body. Two screws 29 secure the cover part to the part 26. The tines 30 of the fork are four in number and are formed in pairs. The two tines of one pair are joined by the arcuate top 31 which, as shown in dotted lines in Fig. 2, is received in a depression in the upper part 26 of the body. This affords a secure means for holding the tines in place in the body, as well as a construction by which renewal of the

tines may be effected. The ends of the tail 20 of the fork extend along recesses formed in the upper surface of the body part 26 and have their ends at right angles to the 5 length of their bodies and are received in vertical holes in the body part 26. A pull exerted upon the tail of the fork is thereby transmitted to the body part 26 and through it to the slide in a manner which prevents 10 any change in the position of the barb-engaging portion of the tail with respect to the slide. The cover part 27 of the fork body is provided with slight depressions to receive the arcuate parts of the tines and 15 with longitudinal grooves to receive the tail slides. The body part 28 of the fork is provided with two depending ears 32 which are provided to counterbalance the weight of the tines. The body parts 26 and 27 of the 20 fork are made of aluminum, the tines and tail of steel wire, and the screws 29 of steel.

It will be observed that by providing the weft hammer hook with the overhanging finger excessive movements of the fork are prevented and that the inclined surface adjacent to the barb contributes to the proper action of the fork under the influence of the blows to which it is subjected.

Having thus described the invention, what 30 is claimed is:

1. Detector mechanism for looms having, in combination, a detector slide, a detector fork carried by the slide provided with a tail, and a weft hammer provided with a 35 weft hammer hook and a fork guard extending rearwardly from the weft hammer hook above the weft fork for engaging the fork upon excessive upward movement thereof.

2. Detector mechanism for looms having, 40 in combination, a detector slide, a detector fork carried by the slide provided with a tail, and a weft hammer provided with a weft hammer hook and an overhanging fork guard for engaging the fork upon excessive 45 upward movement thereof, the hook having a barb for engagement with the tail and provided with an inclined tail-supporting surface adjacent to the bar for engaging and supporting the tail of the fork and easing 50 its descent to a position in front of the barb upon rearward movement of the hook.

3. Detector mechanism for looms having, 55 in combination, a detector slide provided with a weft hammer hook support, a detector fork pivotally mounted on the slide provided with a tail, and a weft hammer provided with a weft hammer hook, the under side of which is adapted to rest and slide upon the hook support of the detector slide, the hook being provided with a barb for 60 engagement with the tail of the fork and

having an overhanging guard extending upwardly and rearwardly from the body of the hook in the rear of the barb over the body of the tail and adapted upon oscillation of the tail to engage and limit the throw of the tail upon its impact with the yarn, said finger having an inclined tail-supporting surface extending from the barb upwardly and rearwardly and forming the 70 upper surface of the proximal end of the guard.

4. Detector mechanism for looms having, in combination, a detector slide, a detector fork carried by the slide provided with 75 tines and a tail, and a weft hammer provided with a weft hammer hook having an overhanging fork guard extending rearwardly over the body of the fork and adapted to engage the latter upon overthrow of the 80 fork, said hook being also provided with a barb for engagement with the tail upon failure of weft indication.

5. Detector mechanism for looms having, in combination, a detector slide, a detector 85 fork carried by the slide provided with a tail, a weft hammer provided with a weft hammer hook for engaging the tail of the fork, and a spring connection between the weft hammer and the weft hammer hook 90 acting to hold the hook in depressed position.

6. Detector mechanism for looms having, in combination, a detector slide provided 95 with a hook supporting plate, a detector fork carried by the slide provided with a tail, a weft hammer, a weft hammer hook pivotally mounted on the weft hammer and resting on the hook supporting plate of the slide, and a spring connection between the 100 weft hammer and the weft hammer hook acting to hold the hook against the supporting plate so as normally to maintain it in correct operative position with relation to the fork tail.

7. Detector mechanism for looms having, 105 in combination, a detector slide provided with a weft hammer hook support, a detector fork carried by the slide provided with a tail, a weft hammer, a weft hammer hook pivotally mounted on the weft hammer 110 and having a portion resting on and supported by the hook support, the weft hammer hook being provided with a spring carrying portion above the pivot, and a spring 115 in said spring carrying portion of the hook taking against a portion of the weft hammer, tending to turn the hook in a direction to hold it down on the hook support.

In testimony whereof I have signed my name to this specification.

JONAS NORTHIROP.
